Primary Examiner — Garth Rademaker*Assistant Examiner* — Aaron C Fowler(74) *Attorney, Agent, or Firm* — WHDA, LLP(57) **CLAIM**

The ornamental design for a wheel for automobile, as shown and described.

DESCRIPTION

FIG. 1 is a front perspective view of a wheel for automobile showing our new design; and,

FIG. 2 is a front elevation view thereof.

The claimed design is indicated by the relatively dark portion, while the relatively light portions are environmental and form no part of the claimed design.
